UNITED STATES PATENT OFFICE.

FREDERICK HALDEMAN, OF PORTLAND, OREGON.

HEATING APPARATUS.

1,314,396.

Specification of Letters Patent. Patented Aug. 26, 1919.

Application filed July 27, 1918. Serial No. 247,033.

To all whom it may concern:

Be it known that I, FREDERICK HALDEMAN, a citizen of the United States, residing at Portland, in the county of Multnomah 5 and State of Oregon, have invented a new and Improved Heating Apparatus, of which the following is a specification.

My invention, which relates generally to that class of steam or hot water plants, more 10 especially provided for residences and business houses, is more particularly directed to an improved construction of a boiler in which is included an improved arrangement for burning gas, under pressure, and by 15 which the gas and air flames are so directed with respect to the water storage steam drums, that a uniform and maximum heat is provided for contact with the said drums and their connecting coils, before the products of combustion pass off to the chimney 20 or stack.

Another object of my invention is to provide a gas heated boiler construction in which a plurality of individual heating coils 25 and corresponding burner units are utilized and are relatively so arranged that one or more of the said coils and their corresponding burner units may be cut off in the summer or such other time, when not much 30 heat is required.

Another and essential feature of my invention is the provision, in a gas heated boiler construction of the character stated, for causing the flames to follow in the direction of and around the coils as such flames 35 pass from the burner nozzles through the boiler drum or heating space to the offtake or stack.

In its more subordinate nature, my invention 40 embodies certain details and peculiar combination of parts hereinafter fully set forth, specifically stated in the appended claims and illustrated in the accompanying drawings, in which:

Figure 1 is a front elevation of my improved gas heated boiler construction, the front plate and wall of the housing being removed.

Fig. 2 is a side elevation thereof, partly 50 in section, looking in the direction of the arrows on Fig. 1.

Fig. 3 is a horizontal section of a portion thereof, taken substantially on the line 3—3 on Fig. 2, and illustrates the individual 55 burners and the gas and air supplies therefor.

Fig. 4 is a cross section taken substantially on the line 4—4 on Fig. 3 and illustrating one of the burners and its connection, the same being shown on a somewhat 60 enlarged scale.

In the drawings, I have illustrated an arrangement of water and steam drums, heating coils and burners adapted for heating an ordinary five or six room house, it being 65 readily apparent from the drawings that my construction of heating apparatus may be readily modified by widening the housing to take in more coils and burners and for the utilization of more drums, when my invention is to be applied for heating apartments, stores and the like.

In the present showing, the housing includes a main or fire chamber 1, which extends the full width of the housing and 75 from the front plate and wall 2 and 10 to the back or fire-wall 3, of brick.

The housing also includes a supplemental or back chamber 4 that extends the full height of the said housing and constitutes 80 a compartment for the reception of the horizontally disposed return coils 5 that connect with the lower or water drums 6, one of which is located at each end of the fire-chamber, and which coils also connect 85 with a mud drum 70 that extends crosswise of and is located at the bottom of the supplemental compartment 4, the latter, in my construction, also serving as a flue passage for the products of combustion, which pass 90 off through a subterranean passageway to a flue 8 whose inlet 9 extends through the bottom of the chamber 4, as is clearly shown in Fig. 2 of the drawings.

As is best shown in Fig. 2, the upper or 95 steam drums and the lower or water drums have their front ends supported in a front wall 10 and their rear ends supported by the inner or fire-brick wall 3 with the extremities of the said rear ends of the said 100 water and steam drums extended into the chamber 4 to provide for conveniently connecting the laterals 50 of the return coils 5 with the water drums and the taps 11 of the heating coils (presently further explained) 105 with the steam drums.

In my construction of heating apparatus, a series of coils 12, in practice preferably copper coils, are joined at their lower ends with a pipe connection 13 that is common 110 to all of the coils and is located under the front ends of the water drums 6 with which

the opposite ends of the said pipe 13 connect, see Fig. 1.

- 5 The coils 12 extend diagonally upwardly and rearwardly and join with a common pipe connection 14, the ends of which connect with and discharge into the bottoms of the upper or steam drums 7, the connection being with such end portions of the said drums 7 that extend within the compartment 4, the fire-wall 3 having an opening 30 at the upper end that extends across the said wall, which opening also constitutes a passage for the escape of the products of combustion to the chamber 4.
- 10 15 It will be noticed from the drawings, that the coils 12, in my arrangement, are closely wound and provide, as it were, restricted fire passages that extend from the lowermost to the uppermost end thereof.
- 20 17 designates a draft opening in the front plate and front wall.

Coöperative with the series of heating coils 12 is a series of burners 18, one for each coil 12, each of which includes a nozzle 19 that extends through the front wall of the housing and has its ejector end angled to project up a short distance within the passages 16 of their respective coils 12, see Figs. 2 and 4.

30 All of the burners 18 connect with a gas feed pipe 20 and each of such burners has a control valve 21 located outside of the housing.

22 indicates an air supply pipe that has laterals 23, one for each burner, that discharge into the burner nozzle to mix with the gas feed thereto, it being understood the gas pressure to the burners is regulated by their respective control valves.

40 45 To aid in directing the flames from the burners to pass under and around the coils 12, the inner face 31 of the fire-wall 3, is inclined at an angle of lesser degree than the angle of inclination of the coils 12 and such arrangement of the fire-wall combined with the diagonally disposed coils, provides for a gradually restricted heating space between the fire-wall and the upper portion of the coil and thereby tends to overcome a too rapid expansion of the flames or hot air as such flames pass up to the escape 40.

50 55 From the foregoing taken in connection with the drawings, the complete arrangement and the advantages of my construction of heating apparatus will be readily apparent to those skilled in the art to which my invention relates.

60 In operation, the flames from the burners will follow up and around their respective coils 12, as shown by the indicator line α on Fig. 2, and as they pass through the top opening 40, the heat products will take the downward course indicated and pass out to the stack.

65 65 While I have shown and described one

specific embodiment of my invention yet it is obvious that changes in the details of construction, arrangement and design of the parts may be made without departing from the spirit of the invention or the scope of the appended claims, such changes of modifications being those that may be made to suit the particular desires of the user or builder; for instance, instead of employing five coils, a greater or lesser number of coils may be employed, instead of locating the tank 6 at the low level shown in Fig. 2, the tank 6 may be raised somewhat higher above the tank 70, and instead of making the inner face of the back or fire wall on an angle less than the inclination of the coils 12 the said fire wall may be inclined in parallelism with the said coils, and furthermore while I have shown and described my system as particularly adapted for steam heating the same may be utilized for hot water systems as well.

What I claim is:

1. In a heating apparatus of the character stated, the combination of an upper tank and a lower tank, a front wall supporting said tanks, a rear wall supporting said tanks and through which rear wall said tanks project, a down draft flue, a pipe coil vertically inclined, the lower end of which communicates with the lower tank and the upper end of which communicates with the upper tank, said fire wall having an opening through which said coil projects adjacent to the upper tank whereby the interior passage of the coil as a whole communicates with said flue, a burner directed into the lower end of said coil, and a lower off-take from the flue, all being arranged whereby the burner flame will pass along and around said coil into the upper region of said flue, an outflow pipe connected with the upper reservoir and a return flow pipe communicating with the lower reservoir.

2. In a heating apparatus of the character stated, a combustion chamber, at least one steam drum located in the top of said chamber, a water heating drum in the lower part of the said chamber, a pipe coil for each pair of upper and lower drums that connect at their lower end with the front end of the water drum and at the upper end with the rear end of the steam drum, the said combustion chamber including a fire-wall whose front or fire receiving face inclines in the direction of inclination of the coils, a gas burner for each coil that extends through the front wall of the combustion chamber and ejects against the coil, return circulation pipes connecting the pair of drums, a flue and a pass at the upper end of the fire-wall that joins the combustion chamber and the flue.

3. In a heating system of the character stated, a structure including a front wall,

side walls, a back wall and an intermediate wall dividing the structure into a combustion chamber and a flue chamber, said intermediate wall having a passage in its upper end between the combustion chamber and the flue chamber for the products of combustion, heating drums mounted in said structure to lie within said combustion chamber and having one end of each drum projected into said flue chamber, heating coils connecting said drums and projecting through said passage of said intermediate wall whereby said coils will lie partly in the combustion chamber and partly in the flue chamber, means for directing heat against said coils in the combustion chamber, said drums lying within the influence of said heat directing means, an offtake pipe from the highest drum, a mud drum in the flue chamber connected with the lower of the first mentioned drums and a return circulation pipe passing into the flue chamber and connecting with the mud drum, all being arranged substantially as shown and for the purposes described.

4. In a heating apparatus of the character stated, a combustion chamber, at least one pair of drums arranged one above the other, the upper functioning as a steam drum and the lower serving as a water reservoir, a pipe coil connected with the upper and lower drums, said coil extending diagonally in a vertical plane, the lower end of the coil being connected to the lower drum and the upper end of the coil being connected to the upper drum, a fire wall in the combustion chamber inclined in the direction of the inclination of the pipe coil, a flue, an outlet at the upper end of the fire wall that connects with the flue, a supply riser connected to the upper drum and a return pipe in communication with the lower drum, a gas burner projected through the front wall of the combustion chamber and held to eject the flame in the direction of the inclination of the pipe coil.

5. In a heating apparatus of the character stated, a combustion chamber, at least one pair of drums arranged one above the other, the upper operating as a steam drum, the lower serving as a water heater, a pipe coil connecting the upper and lower drums, said coils extending diagonally upward from the water to the steam drum, a fire-wall in the combustion chamber inclined in the direction of the inclination of the pipe coil, a down draft flue, an outlet at the upper end of the fire-wall that connects with the down draft flue, return pipes that join the steam and water drum, a gas burner projected through the front wall of the combustion chamber that ejects the flame in the direction of the inclination of the pipe coil, the said burner having a control valve exterior of the front wall of the combustion chamber

and a valved air feed that discharges into the burner.

6. In a heating apparatus of the character stated, a combustion chamber, at least one pair of drums arranged one above the other, the upper operating as a steam drum, the lower serving as a water heater, a pipe coil connecting the upper and lower drums, said coils extending diagonally upward from the water to the steam drum, a fire-wall in the combustion chamber inclined in the direction of the inclination of the pipe coil, a down draft flue, an outlet at the upper end of the fire-wall that connects with the flue, return pipes that join the steam and water drums, a gas burner projected through the front wall of the combustion chamber that ejects the flame in the direction of the inclination of the pipe coil, the said burner having a control valve exterior of the front wall of the combustion chamber and a valved air feed that discharges into the burner, the said nozzle being angled and projected up within the pipe coil.

7. In a heating apparatus of the character stated, the combination of a water reservoir, a pipe coil, the lower end of which is connected with the water reservoir, said coil having its convolutions in close juxtaposition and inclined upwardly from its entrant end toward its exit end, a combustion chamber in which said reservoir and coil are mounted, a flue at the rear of the combustion chamber with which the interior of the coil as a whole communicates at the upper end of the coil, means for directing a flame into the lower end of the coil as a whole, an off-take duct from the upper end of the coil, a return flow duct in communication with the water reservoir, and means for causing a down draft through the flue to draw the products of combustion through the interior of the coil into the flue and down and out of the apparatus.

8. In a water heating apparatus, the combination of at least one pair of water heating drums, one of which is located above the other, a combustion chamber in which the drums are mounted, an offtake flue, a passage connecting the upper rear end of the combustion chamber and the said flue, a circulating pipe connecting the front end of the lower drum with the rear end of the upper drum, a burner projected under the front end of the lower drum and means for creating a heat circulation around the circulating pipe in passing to the flue outlet, the said means including a bridge wall in the combustion chamber whose fire impacting face inclines in the direction of inclination of the circulating pipe.

9. In a water heating apparatus of the character described; a combustion chamber that includes a fire-wall whose fire impacting face inclines upwardly from the bottom

to the top, a supplemental chamber, a pass in the upper end of the fire-wall that connects the supplemental and combustion chambers, a down draft flue in communication with the supplemental chamber, at least one pair of water heating drums mounted in the combustion chamber, one above the other, the upper one being located above the pass between the two chambers, a circulating system coöperating with the drums, said circulating system including a pipe coil that connects with the front end of the lower

drum and the rear end of the upper drum, and return coils mounted in the supplemental chamber in communication with the lower drum, at least one burner projected through the front wall of the combustion chamber and discharging against the lower end of the pipe coil and means tending to direct a flame as it passes from the burner to the flue passage in the direction of and around the pipe coil.

FREDERICK HALDEMAN.
